DISPLAY CABINET

Joe W. Brooks, 1909 Country Club Drive, and Delma C. Waters, E. Highway 44 Drive, A.W., both of Eustis, Fla. 32326; and Paul J. Ciener, 1560 S. Clayton St., Mount Dora, Fla. 32737

Filed June 14, 1972, Ser. No. 262,772

Term of patent 14 years

Int. Cl. D20—02

U.S. Cl. D6—167

FIG 1

FIG 2

FIG. 3

FIG. 4

FIG. 1 is a rear perspective view of a display cabinet showing our new design;

FIG. 2 is a front elevational view;

FIG. 3 is a top plan view; and

FIG. 4 is a right side elevational view.

The bottom of the display cabinet is plain and unornamented.

We claim:

The ornamental design for a display cabinet, as shown and described.
